UNITED STATES PATENT OFFICE.

FENTON L. ROUSSEAU, OF MANCHESTER, GEORGIA.

CAR-COUPING.

SPECIFICATION forming part of Letters Patent No. 508,344, dated November 7, 1893.

Application filed April 10, 1893. Serial No. 469,774. (No model.)

To all whom it may concern:

Be it known that I, FENTON L. ROUSSEAU, a citizen of the United States, residing at Manchester, in the county of Fulton and State of Georgia, have invented new and useful Improvements in Car-Couplings, of which the following is a specification.

My invention relates to car-couplings of that class termed "twin-jaw" couplings, in which the jaws are pivoted in the draw-heads, and said invention has for its object to provide a car-coupling of the class referred to, novel and simple in construction, economical of manufacture, and strong, efficient and reliable in operation; and in which the twin jaws will automatically interlock to couple the cars thus avoiding the danger, expense and loss of time incident in those car-couplings where it is necessary for an operative to go between the cars to couple them together by hand.

To such ends my invention consists in the novel construction and combination of parts hereinafter described and claimed, reference being made to the accompanying drawings, 25 wherein—

Figure 1, is a broken, sectional plan view of a twin-jaw car coupling embodying my invention. Fig. 2, is a detail perspective view, showing portions of the draw-heads in dotted lines, and Fig. 3, is a detail vertical sectional view of one of the couplings.

In the said drawings, the reference numerals 1, 1, indicate the draw-heads of adjacent cars, which are interiorly chambered horizontally from their forward ends as at 2, and are also recessed at opposite sides as at 3, intermediate their vertical extent in order that the hereinafter described locking jaws may swing or turn laterally a sufficient distance to engage and disengage each other. The recesses 2, are at one side arc-shaped, as at 4, and at the other side are intercepted by projections 5, extending from the side of the draw-heads, which projections are inclined outwardly and rearwardly, to form pockets 5^a. The ends of the draw-heads 1, are concaved at opposite sides as shown at 1^a for a purpose hereinafter mentioned.

The numerals 6, 6, designate the interlocking jaws, the forward portions of which extend outside of the draw-heads and are of the same

dimensions vertically as the draw-heads. The rear portions of said jaws are of reduced dimensions to correspond with the chambers 2, in which they are disposed and pivotally held by pins 7 or other suitable means passing through elongated slots 6^a, formed therein, so that they may swing into and out of interlocking engagement with each other.

The forward ends 8 of the jaws 6, are rounded or convex in form to correspond with the concave portions 1^a of the draw-heads, whereby when said jaws 1 or either of them, are in open position, indicated by dotted lines in Fig. 1, they will automatically come together and interlock, as seen in full lines, Fig. 1, upon contact therewith of the draw-heads. The faces of said jaws 6 opposite the convex or rounded parts 8, are provided with corresponding convex portions 9 and concave portions 10, the concave 10 of one jaw receiving the convex portion of the other.

The tails or heels 11 of the jaws 6, are provided with arc-shaped rear surfaces to correspond to the shape of the rear edge of the chambers 2, in which they are disposed, and at one side are cut away angularly as at 12 to register with the locking pin or key hereinafter described; and at their other sides said jaws are recessed as at 13 to form projections 13^a to fit the pockets 5^a formed in the sides of the draw-heads. The projections 13^a engage the pockets 5^a to limit the lateral swinging movement of the jaws 6, in one direction and in connection with the locking pins 14, 85 bear all the strain on the coupling.

In the manner described the tails or heels of the jaws 6 are made dovetail in form.

The numerals 14, designate rectangular locking pins or keys which are arranged obliquely from the line of draft in vertical rectangular slots 15 provided therefor in the draw-heads. The lower ends of said pins or keys are cut away to provide extensions 16 of reduced diameter, the slots 15 being correspondingly reduced at the under sides of the draw-heads, whereby the pins or keys are prevented from dropping down out of operative position. Those portions of said pins or keys above the extensions 16, engage the angular recesses or cut away portions 12 of the heels 11 of the jaws 6, and serve to lock the projec-

tions 13^a in the pockets 5^a when the jaws are interlocked to couple the cars, and also, in connection with the projections 5 and 13, to bear the strain on the coupling, no strain being imparted to the pins or other devices 7 on which the jaws 6, swing or turn laterally. When the coupling jaws 6, are in open position the lower ends of the pins or keys rest upon the upper surface of the tails or heels 10 of said jaws, and when said jaws are automatically interlocked by the impact of the draw-heads the reduced extensions 16 on said pins drop into the reduced portion of the vertical slots 15, thus automatically locking the 15 dovetailed heels or tails positively from all movement. The upper end of the pins or keys are provided with orifices to engage a crank arm to be operated by the side of the car, or a cord to be operated from the top of the car; 20 or said pins may be otherwise suitably operated to uncouple the cars.

It will be seen that by my invention, I provide a novel car-coupling, simple in construction, economical of manufacture, and strong, 25 durable and efficient in operation, and wherein the strain on the coupling is borne by the draw-heads and the locking jaws independently of the devices which pivot the said jaws in the draw-heads, and wherein, also, the jaws 30 are automatically interlocked and the locking pin is automatically dropped to retain the jaws interlocked.

As shown in the drawings the jaws may be provided with pin holes and recessed intermediate their upper and lower ends in order 35 that when necessary a pin and link may be used in connection therewith.

Having thus described my invention, what I claim is—

1. The combination with a chambered draw-head having a lateral recess or pocket, of a vertically sliding locking pin arranged diagonally to the line of draft, and a jaw pivoted in the draw-head at a point in front of said lateral recess or pocket and provided with a dove-tail heel piece, one portion of which engages the pocket, and the other portion of which engages one side of the vertically sliding locking pin, so that the draft strain on the jaw is thrown entirely on the pin and on the 5c wall of the recess or pocket, substantially as described.

2. The combination with a chambered draw-head having a lateral recess or pocket, of a vertically sliding locking pin angular in cross 55 section and arranged obliquely to the line of draft, and a jaw pivoted in the draw-head by a pin and slot connection at a point in front of said lateral recess or pocket and provided with a dove-tail heel piece, one portion of 60 which bears against the vertically sliding angular locking pin, and the other portion against the wall of the recess or pocket so that the entire draft strain is thrown on the oblique locking pin and on the wall of the recess or 65 pocket, substantially as described.

In testimony whereof I have hereunto set my hand in presence of two subscribing witnesses.

FENTON L. ROUSSEAU.
